UNITED STATES PATENT OFFICE.

JAMES T. ATWOOD, OF ROCKFORD, ILLINOIS.

METHOD OF MANUFACTURING COVERED-JOINT HINGE.

Application filed March 15, 1924. Serial No. 699,463.

This invention relates to hinges, and more particularly, to that type known as "covered joint" hinges, adapted for outdoor use where the hinge joint is exposed to the elements. 5 And, while my invention has reference to hinges of this type for general application, they are especially intended for use in the automotive industry, for hanging automobile body doors.

10 Heretofore, hinges of this type have been produced in the form of malleable castings, or they have been made from flat steel material and so constructed as to include a cover plate or shell supplemental to the outside hinge member and shaped to cover the hinge joint. Such hinges are not altogether satisfactory because of their comparatively high cost of production and because the sheet metal cover plate will not 15 stand the handling which hinges for this use are subjected to, and they frequently are distorted, dented and marred from the blows of a hammer or the effects of other tools used in setting and adjusting the hinges 20 on the door body.

The primary purpose of the present invention is to provide an improved method of manufacturing a covered joint hinge which will resemble in appearance the malleable cast hinges, especially in that the hinge joint will be covered from view and from the corrodin- 25 g effects of the elements, and in which the outer hinge member will cover the hinge joint and present to view a single piece structure which will not dent or mar as will the cover plate type of hinge. This is accomplished in the present embodiment of the invention by making a single piece outer hinge member the knuckle portion of which is in 30 spiral form. The inner convolution of said spiral is the knuckle proper and has trans- 35 verse slots or cuts which receive the complementary portions of the other hinge knuckle and the outer imperforate portion of the spiral houses or covers the hinge joint, that is the joints made by the interfitting 40 knuckles.

45 My invention contemplates forming each hinge member from a single piece of flat steel material of sufficiently heavy gauge to insure the desired strength, wearing qualities and allowance for finish as by grinding or otherwise forming the edges of the outer knuckle to obtain a crowned effect.

It further contemplates the provision of 55 a novel method of making a covered hinge of the character described, particularly the outside hinge member. And, while the improved product claimed in application Serial No. 13,960, filed March 9, 1925, might be 60 produced by other means and methods, that contemplated and disclosed herein is especially advantageous and desirable in promoting economy in the cost of producing 65 said hinges and in insuring the desired accuracy in the resultant machined surfaces forming part of the hinge joint. The steps comprising this method are described hereinafter.

70 Other objects and attendant advantages 70 will be appreciated by those skilled in this art as the invention becomes better understood by reference to the following description when considered in connection with the accompanying drawings, in which— 75

Fig. 1, is an edge view of a covered joint hinge embodying my invention;

Fig. 2, is a view of the rear side of the hinge, looking at the right hand side of Fig. 1;

Fig. 3, is a longitudinal sectional view 80 through the hinge with the hinge members open, taken on the line 3—3 of Fig. 2;

Fig. 4, is a detailed section taken on the line 4—4 of Fig. 2;

Fig. 5, is a view of the inside hinge member;

Fig. 6, is a section taken on the line 6—6 of Fig. 5;

Fig. 7, is a view of the outside hinge mem- 90 ber;

Fig. 8, is a section taken on the line 8—8 of Fig. 7; and

Figs. 9 to 13 are views showing respec- 95 tively the different steps of the method em- 100 ployed in making the outside hinge member.

Referring more particularly to Figs. 1 to 8 inclusive, I will describe first the product, namely, the hinge, and later the method of 105 making it. It will be borne in mind that the particular hinge shown in the drawings is merely a single illustration designed especially for hanging automobile doors, and that in other applications the proportions and dimensions of parts might be varied within the scope of the invention.

The hinge comprises three parts, namely an inner hinge member 14 adapted in this

instance to be attached to the door jamb of the body, an outer hinge member 15 adapted to be attached to the door, and a pivot pin 16 connecting the knuckle of said hinge members. Each hinge member is formed of a single piece of flat steel turned or curled upon itself at one end to provide the knuckle. As shown in Figs. 4 and 6 the inside hinge member is formed at one end to provide a cylindrical knuckle 17 laterally offset from said member, in this case at the side on which it is attached to the body. In this case the knuckle is formed or cut by a suitable machining operation to provide transverse recesses 18 for the reception of the complementary knuckle portions of the other hinge member. The outer hinge member is formed to provide in addition to the usual cylindrical knuckle 19, a knuckle portion designated generally by 21, which covers and conceals the hinge joint from view. This knuckle is substantially in the form of a spiral comprising the knuckle proper 19 disposed within the supplemental knuckle portion 21, the knuckle 19 being substantially a single convolution. Transverse cuts are made in the knuckle 19 to provide recesses having machine surfaces 22 which bear against the complementary bearing surfaces on the other knuckle. The outside hinge member is of uniform thickness or substantially so from end to end, including its knuckle, thereby providing maximum strength throughout its length. In this regard it will be observed that there is no sheet metal shell over the outer hinge member in order to cover the hinge joint and that with the present construction the full thickness of metal is carried throughout the spiral knuckle, giving an integral structure having greater strength and being less apt to get out of alignment or be stressed out of shape, or marred, than covered joint hinges of the multi-part built-up construction.

The pivot pin has an eccentric head 23 for the purpose of overlying or covering the space 24 between the spiral portion 21 and the knuckle proper and also for locating the head centrally with respect to the entire knuckle structure. Suitable means may be employed for preventing rotary displacement of the pivot pin and consequently displacement of its head with respect to the spiral knuckle. In the present case this comprises a small boss 25 on the under side of the head adapted to engage in the recess or opening 26 at the terminus of the knuckle 19.

My invention also contemplates the provision of a method for making the above-described hinge; and while this method is very desirable because it enables the production of hinges at a comparatively low cost and insures uniformity in shape of the hinge members which might otherwise be difficult

to produce in large numbers at a low cost with a sufficient degree of accuracy required, it should nevertheless be understood that my improved hinge might be produced by other methods. The method consists, preferably but not necessarily, in the following steps. The operation of forming the knuckle proper on both the inside and outside hinge member is substantially the same except that the knuckle for the outside hinge member is offset laterally further than the knuckle for the inside hinge member. I prefer to make each hinge member from either cold or hot rolled open hearth flat rolled steel, which is economical, practical, has the desired strength, and is very well suited to being worked into form by my method. Each knuckle will be formed by bending or curling one end of the flat steel blank to provide the cylindrical knuckle above described. I prefer to do this by initially bending or turning one end 27 of the blank laterally as shown in Fig. 9. This is done by placing the blank designated by 15 (to be formed into the outside hinge member), in a bottom die 28 with one end of the blank resting on a ledge 29, and bringing a top die 31 down onto the blank so as to bend or turn the end 27 to conform to the shape of the top and bottom dies as shown. The blank thus formed will then be placed in a knuckle forming die having a substantially semi-circular cavity 32 and a straight wall 33 tangential thereto, with the turned end 27 located in the cavity. A top die 34 having a shoulder 35 engaging the end of the blank opposite from its turned end 27 will in a quick pressure stroke parallel with the plane in which the blank is disposed, force the blank down into the cavity 32 so that its turned or curved end 27 will be curled by the shape of said die cavity 32 to the cylindrical form noted in dotted lines in Fig. 10, the pressure stroke being properly timed in length so that the terminus of the knuckle is brought into close proximity to the body portion of the blank. In this manner one end of the blank is bent or curled to form an imperforate knuckle laterally offset from one side of the plane of the blank body. The blank will then be placed in a die designated generally by 36 having a cavity 37 which from the points 38 to 39 are substantially parabolic and from 39 to 41, arcuate. This die also has a straight wall 42 substantially tangential to the curved face 38-39. An upper pressure die 43 will then force the blank downwardly by endwise pressure thereon thereby further offsetting the knuckle 19 from the body of the blank and at the same time turning the knuckle a predetermined number of degrees in a counter-clockwise direction and curving the portion of the blank adjoining the knuckle proper to conform to the shape 38-39 of the die. The blank thus formed will then be placed in a

suitable fixture designated by 44, Fig. 12, and slotted transversely of its knuckle by a suitable milling cutter 45, or the equivalent, to provide the recesses or slots 22 above mentioned. The cuts are not carried entirely through the blank and therefore leave the outer wall of the knuckle portion 21 uncut or imperforate to the greatest length for covering the hinge joint. The transversely cut blank will then be placed in a die 36¹ of approximately the same shape as the die 36 and given another endwise blow by a pressure die 43¹ similar to the die 43, thereby further curling the knuckle 19 in a counter-clockwise direction, or rolling it in the same direction to provide a spiral knuckle having the characteristics above described. The stroke of the pressure die 43¹ is so regulated in length as to curl, roll or coil the knuckle end to the form shown in Fig. 13, which is the final form of the outside hinge member. It will be observed that the knuckle end of this hinge member is substantially spiral in form, and that by properly shaping the dies a clearance space 45 will be provided between the knuckle proper 19 and the knuckle portion 21 to prevent interference of the latter with the periphery of the complemental knuckle 17 of the inside hinge member when the hinge members are connected together in operative relation. This completes the operation of forming the blank and there only remains such operations as may be required for giving the blank any desired finish and for grinding off any small burrs or rough edges. In the present use of the hinge, above mentioned, it is preferred to grind the corners 46 through part at least of the length of the spiral knuckle portion 21 to give it a crowned effect, this being purely for finish and made possible to a greater degree without impairing the strength than may be done with the metal shell type of covered joint hinge above described. An important advantage in the manufacture of the outer hinge member according to the method disclosed herein is that the bearing surfaces for the hinge joint will be smooth and close fitting. This is because such surfaces may be accurately machined after the knuckle proper has been formed and the blank is subsequently turned, curled or coiled upon the knuckle proper without displacing the relative relation of the machined surfaces.

It will be noted that the reference to top and bottom die members is merely relative and that the several forming operations might be performed in any suitable plane other than vertical as herein disclosed. The dies employed in the practice of my method are preferably used in a punch press, the lower dies being carried on the stationary bed and the upper dies by the plunger. It should be understood however that my meth-

od is not to be circumscribed by the use of apparatus other than that disclosed therein, nor is the product by its manufacture by a method other than that claimed herein.

It is believed that the foregoing conveys a clear understanding of the objects prefaced above, and while I have illustrated but a single practical embodiment of my improved hinge and method of making it, it should be understood that details in the hinge construction might be made and the method might be varied and even other methods employed for producing said hinge without departing from the spirit and scope of the invention as expressed in the appended claims, in which—

1. The method of making a hinge member of a covered joint hinge, consisting in bending one end of a metal blank substantially a complete convolution providing a knuckle, slotting said knuckle transversely for the reception of a complemental knuckle, and bending the blank about said knuckle in spiral form providing an outer knuckle portion adapted to cover the hinge joint.

2. The method of making the outside hinge member of a covered joint hinge, consisting in bending one end of a blank to form a knuckle, slotting the knuckle transversely, and rolling the knuckle upon the blank in spiral form providing an outer knuckle portion adapted to cover the hinge joint.

3. The method of making the outside hinge member of a covered joint hinge, consisting in forming a transversely recessed knuckle on one end of a metal blank, and rolling the blank about said knuckle to spiral form in which the outer imperforate portion of the knuckle covers the inner perforate knuckle proper.

4. The method of making the outside hinge member of a covered joint hinge, consisting in bending one end of a metal blank to form a cylindrical knuckle joined tangentially to the body of the blank, bending the blank to turn said knuckle a predetermined number of degrees in the same direction as the first mentioned turn to position the knuckle in a plane laterally spaced from the plane of the blank body, slotting the knuckle transversely for reception of a complemental knuckle, and further bending the blank to turn the knuckle an additional predetermined number of degrees in said direction to provide a spiral knuckle including said cylindrical knuckle proper at its center.

5. The method of making a hinge member of a covered joint hinge, consisting in curling one end of a flat metal blank substantially a complete convolution to form an imperforate knuckle offset at one side of the plane of the blank body, bending the knuckle end of the blank laterally so that the knuckle is further offset from said plane, slotting said knuckle transversely for the reception of a

complemental knuckle, and curling the blank upon said knuckle to spiral form in which the transversely perforate knuckle is positioned at the inner side of the imperforate curved portion of the spiral knuckle.

6. The method of making a covered joint hinge member, consisting in bending one end of a metal blank to provide a knuckle, milling the knuckle by a transverse cutting operation to provide machined bearing surfaces for the knuckle of a complemental hinge member, and bending or curling the blank about the machined knuckle to provide a cover for the knuckle joint.

7. The method of manufacturing the outer member of a covered joint hinge consisting in curling one end of a metal blank to provide a substantially cylindrical knuckle portion, slotting said knuckle portion for the reception of the knuckle of the inside hinge member, and further curling the blank upon said knuckle portion to provide an outer imperforate portion spaced from and providing a covering for the slotted knuckle portion.

8. The method of manufacturing the outer member of a covered joint hinge consisting in curling one end of a metal blank by successive operations to provide a spiral knuckle, and slotting the knuckle portion transversely before the final curling operation.

9. The method of manufacturing the outer member of a covered joint hinge consisting in bending one end of a metal blank by successive operations to provide a knuckle laterally offset from the plane of the body proper of the blank, said operations including bending said end upon itself so as to substantially define the shape of the knuckle proper and subsequently bending said end to the finished shape, and transversely slotting the knuckle after the first-mentioned bending operation and prior to said finished bending operation, the said subsequent bending operation serving to conceal the slots formed in the intermediate operation.

10. The method of manufacturing the outer member of a covered joint hinge consisting in providing a single piece metal blank, forming a knuckle on one end of said metal blank by a series of bending operations, one of said operations consisting in turning the end of the blank back upon itself to substantially define the shape of the knuckle proper and the pivot pin hole and a subsequent bending operation consisting in completing the shape of the knuckle, and transversely slotting the knuckle after the first-mentioned bending operation and prior to the subsequent bending operation, the latter operation serving to conceal the slots formed in the intermediate operation.

11. The method of manufacturing the

outer member of a covered joint hinge consisting in providing a single piece metal blank, forming a knuckle on one end of said metal blank by a series of bending operations, one of said operations consisting in 70 turning the end of the blank back upon itself to partially shape the knuckle and a subsequent bending operation consisting in completing the location of the knuckle with respect to the body of the hinge member, 75 and slotting the knuckle after the first-mentioned bending operation and prior to said subsequent bending operation, the latter operation serving to conceal the slots formed in the intermediate operation.

12. The method of manufacturing the outer member of a covered joint hinge including bending one end of a metal blank to partially shape the knuckle, transversely slotting said bent end for the reception of the knuckle of the complemental hinge member, said slots reaching beyond the peripheral dimension of the knuckle proper into the body of the blank to provide clearance for the periphery of the complemental knuckle portions, and subsequently bending said knuckle proper to a position in which the unslotted portion covers the hinge joint made by the interfitting knuckles.

13. The method of manufacturing the outer member of a covered joint hinge consisting in turning one end of a metal blank to partially form the knuckle proper, then transversely slotting said turned end, and curling said turned, slotted knuckle portion to provide a laterally offset knuckle in which an imperforate portion has been disposed by said curling operation in a position to cover a portion of the hinge joint made by the interfitting knuckles.

14. The method of manufacturing a hinge member consisting in forming one end of a metal blank substantially to the shape of a knuckle, transversely slotting said knuckle portion, and subsequently curling said slotted knuckle portion to provide a laterally offset knuckle, the unslotted outer side of the blank body contiguous to the slot openings thereat being advanced by said curling operation to a position covering in part the hinge joint made by the interfitting knuckles.

15. The method of manufacturing the outer member of a covered joint hinge consisting in forming one end of a metal blank to provide a knuckle, transversely slotting said knuckle so that the slots extend into the body of the blank to provide clearance space for the knuckle of the complemental hinge member but so as not to penetrate the outer surface of said body, and subsequently curling said slotted knuckle portion to advance it to a position in which the imperforate portion of the body covers in part the hinge joint made by the interfitting knuckles.

16. The method of manufacturing the outer member of a covered joint hinge consisting in forming by successive bending operations one end of a metal blank to provide 5 a laterally offset knuckle, and machining said knuckle prior to the final bending operation to provide bearing surfaces for the knuckle portion of the complementary hinge member, said machining operation leaving 10 an imperforate body at the periphery of said knuckle portions, which imperforate body portion is positioned by the bending

to cover in part the hinge joint made by the interfitting knuckles.

17. The method of manufacturing a hinge member of the character described consisting in bending one end of a metal blank to provide a knuckle form, transversely slotting said knuckle form, and subsequently curling the slotted knuckle form by endwise pressure on the blank to complete the shape of the knuckle and to conceal the slots formed in the intermediate operation.

JAMES T. ATWOOD.
